UNITED STATES PATENT OFFICE.

THEODORE R. VINZENT, OF OAKLAND, CALIFORNIA.

NAIL FOR WIRE LATH.

Application filed August 1, 1922. Serial No. 578,914.

To all whom it may concern:

Be it known that I, THEODORE R. VINZENT, a citizen of the United States, residing at Oakland, county of Alameda, and State of California, have invented new and useful Improvements in Nails for Wire Lath, of which the following is a specification.

This invention relates to a nail or fastener for wire lath, the object being to provide a nail which will serve not only as a spacer for the lath, but likewise a fastener and will insure even spacing of the lath, at the same time being capable of application to the lath with the greatest ease and facility.

One form which my invention may assume is exemplified in the following description and illustrated in the accompanying drawing, in which—

20 Figs. 1 and 2 show side elevations of a nail embodying my invention.

Fig. 3 shows a plan view of a section of a wall fitted with wire lath, the latter being spaced and held in position by nails such as 25 shown in Figs. 1 and 2.

Fig. 4 shows an edge view of the parts illustrated in Fig. 3.

For the purpose of illustrating the manner of using my invention, I show a wall 10 over which is arranged wire lath 11. The lath is spaced from the wall and held in place by nails 12 placed at suitable intervals.

This nail which constitutes the present invention is of a novel form and consists of a twisted shank portion 13 and a looped end 14 forming the head of the nail. The loop terminates in a downwardly inclined extension 15, which is spaced laterally from the shank.

In use, the nail is arranged alongside one of the strands of the wire lath with the projecting portion 15 overhanging the strand. The nail is then driven into the wall, and, owing to the helical convolutions in the shank resulting from the twisting of the shank, the nail will turn screw-fashion while being driven. Thereby the projecting end portion 15 will move beneath the strand and guide the latter into position

within the loop. When the nail is finally driven home a kink, as shown at 16, will be formed in the strand, thereby tightening the wire lath and causing it to be evenly spaced from the wall at all points. The projecting end of the loop is so shaped as not to enter the wall, but merely rides upon the surface thereof, as clearly indicated in Fig. 4.

The nail is preferably formed of wire and its manufacture can be accomplished at 55 small cost, the various steps consisting of cutting the wire into proper lengths, twisting the shank portion and forming a loop in the head thereof. The application of the nail to the wire lath can be done by the ordinary workman and requires no more time than the driving of an ordinary nail. The final result is a correct and even spacing of the wire lath and the tightening thereof so that all parts of the lath will be spaced from 60 the wall.

Various changes in the construction, combination and arrangement of the several parts herein shown and described may be employed without departing from the spirit 75 of my invention as disclosed in the appended claims.

It is obvious the twisting or threading of the shank may be omitted, if desired, and the nail rotated by manually turning the 80 same with the claws of a hammer.

Having thus described my invention, what I claim and desire to secure by Letters Patent is:

1. A fastener for wire lath comprising 85 a nail having its shank formed with a helical convolution to cause the nail to turn when being driven into a wall, and a loop forming the head of the nail, said loop terminating with a projecting portion inclined 90 downwardly and spaced laterally from the shank and adapted to be moved beneath a strand of wire to guide the same within the loop while the nail is being driven.

2. A fastener for wire lath comprising 95 a nail having its shank twisted to form a helical convolution whereby to cause the nail to turn when it is being driven, a loop forming the head of the nail, said loop terminating in a downwardly inclined projecting portion 100

spaced laterally from the shank and adapted to move beneath a strand of wire as the nail is being driven whereby to guide the strand into the loop, said projecting end being adapted to seat upon the surface of the wall when the nail is driven home.

3. A fastener for use with metal lath com-

prising a nail having its head formed with a loop, the end of the loop continuing downwardly and to one side of the shank to engage beneath the strand of a wire for the purpose of guiding the strand into the loop when the nail is turned.

THEODORE R. VINZENT.
